Fig. 1.

UNITED STATES PATENT OFFICE

2,260,785

DOOR HANDLE

Antone Miguel, San Francisco, Calif.

Application July 10, 1940, Serial No. 344,796

5 Claims. (Cl. 70—208)

The present invention relates to improvements in door handles and is more especially directed to the type particularly applicable to the doors of the closed bodies of motor vehicles.

An important object of the invention is to provide a door handle embodying means whereby it can be pushed into a recess in the door so as to lie substantially flush with the door body to preclude unauthorized opening of the door.

Another object of the invention resides in the provision of a door actuating handle for motor vehicles, airplanes and the like in which the handle is made up of a plurality of telescoping sections surrounding the door lock spindle, said handle being collapsible within a recess formed in the door body and locked therein to eliminate the possibility of the handle catching in the clothes of a pedestrian while the vehicle is in motion and at the same time preclude unauthorized opening of the door.

The invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in which:

Figure 1 is a longitudinal sectional view through a portion of a car door and illustrating the invention in use.

Figure 2 is a detail sectional view taken substantially on line 2—2 of Figure 1.

Figure 3 is a detail sectional view taken substantially on line 3—3 of Figure 1.

Referring to the drawing for a more detailed description thereof, the numeral 5 generally designates a car door and the door frame is generally designated by the reference numeral 6. The interior of the door 5 is hollow and has attached to the inner face thereof a latching mechanism 7 including a latch bolt 8 adapted to fit within a keeper recess 9 for maintaining the door in closed position. The latch bolt 8 is actuated by means of a spindle 10 and in accordance with the present invention, said spindle is hollow and supports therein a coiled tension spring 11 for a purpose to be hereinafter described.

The outer face 12 of the door 5 is formed with a depressed portion or recess 13 adapted to confine the door handle 14 as said handle is telescoped. In Figure 1 of the drawing the handle is shown in full lines resting within the re-

cess 13 and the broken lines illustrate the position of the handle when opening the door.

As more particularly shown in Figure 3 of the drawing, the hollow spindle 10 is substantially square-shaped in cross section and the means for actuating said spindle to release the latch bolt 8 from the recess 9 comprises substantially square-shaped sections 15, 16 and 17 surrounding the spindle 10 and arranged in telescoping relation. As more clearly shown in Figure 1 of the drawing, the section 17 telescopes within the section 16 and both sections telescope within the section 15. The section 15 is formed with an annular flange 18 having diametrically opposed slots 19 formed therein and the sections 16 and 17 are formed with outwardly and inwardly extending flanges 20 and 21, respectively, adapted to prevent disengagement of the sections when in extended position. The inner end of the section 15 is also formed with an inwardly extending flange 22 and as shown in broken lines in Figure 1 of the drawing, when the sections are in extended position the outwardly and inwardly extending flanges 20 and 22 of the sections 16 and 15, respectively, and the outwardly and inwardly extending flanges 20 and 21 of the sections 17 and 16, respectively, will be in engagement. The actuating handle 14 is attached by any desired means to the section 17.

30 A pair of plates 23 are attached by any desired means to the inner face 24 of the recess 13, said plates being formed with inwardly extending lugs 25. When telescoping the sections of the door handle or permitting the extension thereof, it is necessary to effect a slight rotation of the handle so as to permit the slots 19 of the flange 18 to align with the lugs 25. In other words, when the sections are telescoped, as shown in full lines in Figure 1 of the drawing and it is desired to release said extensions so as to open the door, the locking means for the handle, to be hereinafter described, is first released, and the coiled spring 11 which is in engagement with the handle 14 will urge said handle and the sections 40 outwardly until the flange 18 abuts the lugs 25. A slight rotation of the handle sections will bring the slots 19 into alignment with the lugs 25 permitting said flange to pass through the lugs and into engagement with the inner face of the recess 13. Then a slight rotation of the handle in the opposite direction will bring the slots 19 out of alignment with the lugs 25 to cause the flange 18 to be held within the lugs 25. In this position, the handle 14 is engaged by the operator and rotation thereof will rotate the spindle 10 to re-

lease the latch bolt 8. When desiring to push the handle into the recess 13, a slight turn of the sections will bring the slots 19 into registry with the lugs 25 and inward pressure will permit disengagement of the flange 18 from the lugs 25 permitting the sections to be telescoped against the tension of the spring 11.

A means has also been provided for locking the handle 14 within the recess 13, said means including a lever 26 adapted to fit within a slot 27 formed in the face 24. The lever 26 is carried on a shaft 28 of a tumbler lock 29 and is adapted to be released by means of a key, not shown. The lever 26 will be held within the door and is formed with a flanged end 30 of a size to fit within the slot 31. The handle 14 is formed with a slot 31 in registry with the slot 27 when said handle is locked within the recess 13. The end 30 of the lever 26 projects through the slots 27 and 31 for locking the handle, it being understood that the slot 31 is of substantially the same shape and size as the flanged end 30. Insertion of a key within the tumbler 29 and rotation thereof will release the end 30 of the lever 26 from the slot 31.

With the handle 14 disposed within the recess 13 unauthorized opening of the door 5 is precluded, but the door can be opened and closed from the interior of the vehicle in the conventional manner. However, in order to open the door from outside of the vehicle, it is necessary to release the locking lever by means of a proper key and as soon as the lever is released from the slot 31, the spring 11 will urge the handle 14 and sections 15, 16 and 17 outwardly. Complete extension of the sections is not accomplished, however, until the flange 18 has been confined within the lugs 25. Since the sections 15, 16 and 17 and spindle 10 are square-shaped in cross section, they will rotate in unison upon actuation of the handle 14.

Also it will be understood, of course, by those skilled in the art that variations in the hereinabove described device involving the substitution of substantial equivalents for the devices described are intended to be comprehended within the spirit of the present invention and that the invention is capable of extended application and is not confined to the exact showing of the drawing nor to the precise construction described and, therefore, such changes and modifications may be made therein as do not affect the spirit of the invention nor exceed the scope thereof as expressed in the appended claims.

What is claimed is:

1. In a door having a latch bolt and spindle means for actuating the same, said door having a recess in its outer face, the improvement which comprises interconnected telescoping sections surrounding said spindle means, a handle secured to one of said sections and adapted to be confined within said recess upon collapsing said sections, a plate attached to the inner face of said recessed portion, means on said plate for holding one of said sections when in extended position, and means for locking said handle within said recess.

2. In a door having a latch bolt and a substan-

tially square-shaped spindle for actuating the same, said door having a recess in its outer face, the improvement which comprises a multiplicity of interconnected substantially square-shaped sections surrounding said spindle, a handle attached to one of said sections and adapted to be confined within said recess when said sections are in collapsed position, spring means within said spindle having one end in engagement with said handle for urging said sections to extended position, a pair of plates attached to the inner face of said recessed portion and having lugs surrounding said sections, one of said sections being formed with an annular flange adapted to be held beneath said lugs when said sections are in extended position, and means for locking said handle in collapsed position.

3. In a door latch having a latch bolt and spindle means for actuating the same, said door having a recess in its outer face, the improvement which comprises interconnected telescoping sections surrounding said spindle means, a handle secured to one of said sections and adapted to be confined within said recess upon collapsing said sections, means on the inner face of said recessed portion for holding one of said sections when in extended position, and means for locking said handle within said recess.

4. In a door latch having a latch bolt and a substantially square shaped spindle for actuating the same, said door having a recess in its outer face, the improvement which comprises a multiplicity of interconnected substantially square shaped sections surrounding said spindle, a handle attached to one of said sections and adapted to be confined within said recess when said sections are in collapsed position, spring means within said spindle having one end in engagement with said handle for urging said sections to extended position, a pair of plates attached to the inner face of said recessed portion and having integrally formed lugs surrounding said sections, and an annular flange formed on one of said sections adapted to be held beneath said lugs when said sections are in extended position.

5. In a door having a latch bolt and a substantially square shaped spindle for actuating the same, said door having a recess in its outer face, the improvement which comprises a multiplicity of interconnected substantially square shaped sections surrounding said spindle, a handle attached to one of said sections and adapted to be confined within said recess when said sections are in collapsed position, a pair of plates attached to the inner face of said recessed portion and having integrally formed lugs surrounding said sections, one of said sections being formed with an annular flange adapted to be held beneath said lugs when said sections are in extended position, means for locking said handle in said recess, said means including a tumbler mounted in the door, and a lever actuated by said tumbler, said lever having a flanged end adapted to engage a slot formed in said handle when said handle is disposed within said recess.

ANTONE MIGUEL.
